UNITED STATES PATENT OFFICE.

WILLIAM W. KNORPP, OF BROOKLYN, NEW YORK, ASSIGNOR TO KNORPP CANDY COMPANY, OF NEW YORK, N. Y., A CORPORATION OF NEW YORK.

DESIGN FOR MARSHMALLOW CANDY.

Application filed May 6, 1927. Serial No. 21,872 Term of patent 14 years.

To all whom it may concern:

Be it known that I, WILLIAM W. KNORPP, a citizen of the United States, residing at Brooklyn, county of Kings, State of New York, have invented a new, original and ornamental Design for Marshmallow Candy, of which the following is a specification.

The present invention comprises a design for marshmallow candy as disclosed in the accompanying drawing forming a part hereof.

Fig. 1 is a front elevational view of the invention.

Fig. 2 is a side elevational view of the invention.

Fig. 3 is a back elevational view of the invention.

I claim:

The ornamental design for marshmallow candy as shown.

WILLIAM W. KNORPP.
